DESIGN FOR A COMBINED FLOWER BOWL AND MIRROR

Horace A. Fuld, New York, N. Y.

Application December 9, 1941, Serial No. 104,551

Term of patent 3½ years

To all whom it may concern:

Be it known that I, Horace A. Fuld, a citizen of the United States of America, residing in New York city, county of New York, and State of New York, have invented a new, original, and ornamental Design for a Combined Flower Bowl and Mirror, of which the following is a specification, reference being had to the accompanying drawing, forming part thereof, wherein

Figure 1 is an elevational view of a combined flower bowl and mirror showing my new design, and

I claim:

The ornamental design for a combined flower bowl and mirror, substantially as shown.

HORACE A. FULD.
